UNITED STATES PATENT OFFICE.

JAMES NOAD, OF EAST HAM, ENGLAND.

APPARATUS FOR DISTILLING SHALE AND OTHER BITUMINOUS SUBSTANCES.

985,053.

Specification of Letters Patent. Patented Feb. 21, 1911.

Application filed August 4, 1910. Serial No. 575,402.

To all whom it may concern:

Be it known that I, JAMES NOAD, a subject of the King of Great Britain and Ireland, and a resident of East Ham, Essex, England, have invented certain new and useful Improvements in Apparatus for Distilling Shale and other Bituminous Substances; and I do hereby declare the following to be a full, clear, and exact description of the same.

10 This invention relates to improvements in apparatus for distilling shale and other bituminous substances.

The invention has for its object to insure 15 the gradual and uniform heating of the shale or the like being treated, and to avoid the uneven heating which occurs at the sides and center of the customary vertical retorts, and the difficulties of firing incidental 20 to the use of horizontal retorts.

According to the present invention the improved retort or still has sides of a stepped cylindrical formation, and is arranged with its widest diameter uppermost and its 25 smaller diameter lowermost so that its inside presents a series of horizontal or approximately horizontal concentric ledges. The retort is set in the combustion chamber or flue of a furnace so that the outside of the 30 retort is exposed to the heat of the latter, the lowermost part of the retort being subjected to the greatest heat. Inside the retort, are arranged rotary rakes or arms which are 35 gradually work the substance under treatment, which is fed onto the highermost ledge through suitably placed hoppers, around the ledges and down from ledge to ledge. The 40 exhausted shale is discharged at the bottom 45 of the retort, and the vapors evolved from the shale are led off from the still head to any suitable condensing apparatus wherein the products are recovered in known manner. The substance under treatment is thus caused to take a prolonged path in descending through the retort to the discharge outlet and its whole mass is gradually and evenly subjected to the increased temperature.

50 The invention is illustrated in the accompanying drawings, in which:—

Figure 1, is a sectional elevation; Fig. 2, is a plan; Fig. 3, is a sectional elevation at right angles to Fig. 1; Fig. 4, is a sectional plan on 4—4, Fig. 3.

Referring to the drawings, A, is the retort constructed of a stepped cylindrical formation as aforesaid. The retort is set in a fire brick chamber, B, having its upper inside part of an inverted conical formation, 60 as at b¹, and its lower inside part of a cylindrical formation, as at b². A combustion space or flue, b³, is thus left between the retort and the chamber wall. The retort is made with a central discharge, a¹, at its 65 lower end leading into a pit, H, which is provided with a conveyer, D, for removing the spent portions of the shale or the like from the apparatus. Furnaces, E, are fitted on each side of the pit and underneath the 70 combustion or flue space for heating the retort, and are connected to a chimney, not shown, by flues, b⁴.

b⁵ indicates openings in the walls of the firebrick chamber B, permitting access to the 75 furnaces.

F are rakes or arms mounted on a vertical shaft, f¹, passing axially through the retort and supported in upper and lower bearings, e¹, e². The shaft is driven externally 80 of the retort by a worm wheel, G, and worm, g¹, off a shaft, g², or in any other convenient manner. The shaft, g², is adapted to drive the conveyer, by wheels or pulleys, g³, and d¹, and a chain or belt, L, at a suitable speed. 85

I are hoppers for feeding the shale or other bituminous substance into the retort. The hoppers are furnished with slides, i¹, or other suitable devices for insuring a regular supply of the substance to be treated, 90 which is preferably ground or broken up before being introduced into the retort. The slides, i¹, are normally closed by springs, i², and are adapted to be moved inward so as to uncover the openings, i³, by a rotary 95 arm, J, on the shaft, f¹. There is no necessity for the provision of means for independently regulating the supply and discharge of the substance, as the conveyer is adapted to discharge from the retort the 100 maximum quantity of substance the hoppers are adapted to feed into the retort.

Steam may be fed into the lower part of the retort through a pipe, K, to aid in conveying the oil vapors from the head of the 105 retort, and by becoming superheated to aid in heating up the substance in the upper part of the retort, in a well known manner. In lieu of steam, water may be fed into the pipe K.

What I claim as my invention and desire to secure by Letters-Patent is:—

1. In apparatus for distilling shale and other bituminous substances, in combination, a furnace, a retort having sides of a stepped cylindrical formation and arranged in the combustion chamber or flue of the furnace with its widest diameter uppermost and its smallest diameter lowermost so that the inside 10 presents a series of horizontal or approximately horizontal concentric ledges of lessening diameter, means for feeding the material onto the highermost ledge, and means for working the material around the ledges and 15 down from ledge to ledge to a discharge outlet, substantially as described.
2. In apparatus for distilling shale and other bituminous substances, in combination, a furnace, a retort having sides of a stepped 20 cylindrical formation and arranged in the combustion chamber or flue of the furnace with its widest diameter uppermost and its smallest diameter lowermost so that the inside 25 presents a series of horizontal or approximately horizontal concentric ledges, means for intermittently feeding the material onto the highermost ledge, and rotary rakes or arms adapted to sweep around said
3. In apparatus for distilling shale and other bituminous substances, in combination, a furnace, a retort having sides of a stepped 30 cylindrical formation and arranged in the combustion chamber or flue of the furnace with its widest diameter uppermost and its smallest diameter lowermost as described. 35
3. In apparatus for distilling shale and other bituminous substances, in combination, a furnace, a retort having sides of a stepped 40 cylindrical formation and arranged in the combustion chamber or flue of the furnace with its widest diameter uppermost and its smallest diameter lowermost so that the inside 45 presents a series of horizontal or approximately horizontal concentric ledges, means for feeding the material onto the highermost ledge, rakes or arms mounted on a rotary shaft and adapted to work the substance under treatment around the ledges and down from ledge to ledge to a central 50 discharge pit, and a conveyer driven on said shaft and adapted to remove the treated substance from the apparatus, substantially as described.

In testimony whereof I affix my signature in presence of two subscribing witnesses.

JAMES NOAD.
